Specification for Design.

Patented June 20, 1922.

Application filed October 31, 1921. Serial No. 511,933. Term of patent 14 years.

To all whom it may concern:

Be it known that I, WILLIAM CODMAN, a citizen of the United States, residing in the city of Providence, county of Providence, State of Rhode Island, have invented a new, original, and ornamental Design for a Handle for a Spoon, Fork, or Similar Article, of which the following is a specification, reference being had to the accompanying drawing, which forms part of the same and in which—

Fig. 1 is a top view of a handle of a spoon or fork showing my new design; and

Fig. 2 is a corresponding sectional view taken along the line 2—2 of Fig. 1, showing the profile of the face of the handle to which this design is applied.

I claim:

The ornamental design for a handle for a spoon, fork or similar article, substantially as shown.

WILLIAM CODMAN.
